RATCHET HANDLE FOR HOIST
Frank J. Lock, Philadelphia, Pa., assignor to Yale & Towne, Inc., New York, N.Y., a corporation of Ohio
Filed Mar. 24, 1964, Ser. No. 354,402
3 Claims. (Cl. 74—157)

This invention relates to a hoist having a ratchet handle or lever by which the hoist is operated. More particularly, the invention relates to the pawl arrangement for the ratchet handle.

Ratchet handles for hoists conventionally include either a reciprocating pawl having a single pawl tooth for engagement with ratchet teeth on the operating shaft of the hoist or a pivotally mounted pawl having two pawl teeth either of which may be engaged with the ratchet teeth. With the first type of pawl, the direction of operation of the hoist is reverse, by withdrawing and reversing the pawl. With the second type of pawl, the direction of operation of the hoist is reversed by pivoting the pawl to engage one or the other of the pawl teeth with the ratchet teeth. Of the two types of pawls, the second type is preferred, as it may be used with a ratchet having generally triangular shaped teeth, while the first type of pawl requires a ratchet having generally square teeth. The triangular teeth provide easier engagement of the pawl with the teeth and allow a greater number of teeth to be used for the same sized ratchet, thereby providing smaller increments of adjustment.

This invention provides an improved pawl arrangement of the second type which is simpler, less expensive and more efficient than those heretofore used. To this end, the arrangement of the invention includes two pawls, in contrast to the prior arrangements in which a single pawl is used with two pawl teeth. The two pawls of the arrangement of the invention are mounted in crossed or scissors fashion on a common pivot, with the pawl teeth of the two pawls extending from one side of the pivot toward the ratchet teeth on the operating shaft of the hoist and extensions of the pawls extending from the other side of the pivot. A single, simple spring extends around the extensions of the pawls and urges the extensions toward each other whereby to urge the pawl teeth toward each other. A cam member extends between the extensions of the pawls and in a neutral position holds the pawls out of engagement with the ratchet teeth. When it is desired to engage one of the pawls with the ratchet teeth, the cam is rotated to force the other pawl further away from the ratchet teeth, while allowing the first pawl to be moved through the force of the spring into engagement with the ratchet teeth. If it is desired to engage the other pawl with the ratchet teeth, the cam is merely rotated in the opposite direction to force the first pawl away from the ratchet teeth whereby the spring forces the other pawl into engagement with the ratchet teeth.

By this arrangement of two pawls mounted in scissors fashion with a spring extending around extensions of the pawls, the movement of one pawl away from the ratchet teeth by the cam actually increases the force with which the spring urges the other pawl into engagement with the ratchet teeth thereby increasing the efficiency of the spring for the purpose of engagement of the pawl. Further, with two pawls, if one of the pawls should break, only a small, single pawl has to be replaced. This, of course, is in contrast to the prior arrangement in which the large pawl with two pawl teeth must be replaced, if one of the pawl's teeth should break.

I have thus outlined rather broadly the more important features of my invention in order that the detailed description thereof that follows may be better understood,

2

and in order that my contribution to the art may be better appreciated. There are, of course, additional features of my invention that will be described herein-after and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

FIG. 1 is a side elevational view of a hoist incorporating a handle pawl arrangement constructed in accordance with the invention,

FIG. 2 is a sectional view taken on the line 2—2 of FIG. 1,

FIG. 3 is a sectional view taken on the line 3—3 of FIG. 2,

FIG. 4 is a sectional view, similar to FIG. 3, but showing one of the pawls engaged with the ratchet teeth on the operating shaft, and

FIG. 5 is a perspective, exploded view of the two pawls, showing the structure and assembly thereof.

Referring to the drawings and in particular to FIG. 1, there is shown a hoist 10 having a ratchet handle 11 incorporating a pawl arrangement constructed in accordance with the invention. While not shown in the drawings, the handle 11 is of substantial length to provide mechanical advantages in operating the hoist and allowing the operator to grasp the handle with both hands.

Except for the pawl arrangement of handle 11 and the shape of the ratchet teeth, the hoist 10 may be of any conventional construction having an operating shaft, as shown at 12 in FIG. 2, which when rotated in one direction effects lifting of a hook 13 through a chain 14 and when rotated in the opposite direction effects lowering of the hook 13. For example, the hoist construction shown in my copending application, Serial No. 91,241, filed February 23, 1961, now Patent Number 3,138,231, may be used.

As best shown in FIGS. 2, 3 and 4, the operating shaft 12 has triangular shaped ratchet teeth 15 formed in the periphery thereof, and the end of the handle 11 is mounted for rotation of the shaft 12, with the shaft 12 extending through an opening 16 formed through the end of the handle 11. The handle 11 is retained on the shaft 12 by a suitable retaining ring 16a.

The pawl arrangement of the invention by which the handle 11 may be connected to the operating shaft 12 so that the shaft 12 may be rotated in either direction by short pumping strokes of the handle 11 includes, as best shown in FIGS. 3 and 4, two pawls 17 and 18. The two pawls 17 and 18 are mounted in scissors fashion on a common pivot pin 19, with pawl teeth 20 and 21 thereof extending from one side of the pivot pin 19 toward the ratchet teeth 15 on the operating shaft 12, and extensions 22 and 23 of the pawls extending on the opposite side of the pivot pin 19.

A simple C-shaped spring 24 extends around the extensions 22 and 23 and urges the extensions 22 and 23 toward each other to urge the pawl teeth 20 and 21 toward each other and toward the ratchet teeth 15. The C-shaped spring 24 is held assembled to the pawls 17 and 18 by engagement of the ends of the spring in recesses 25 and 26 formed in the sides of the extensions 22 and 23 of the pawls.

As best shown in FIG. 5, the pawls 17 and 18 are made identical and provided with cut-away portions 27 and 28 on one side thereof. In assembling the pawls 17 and

18, one of the pawls is reversed and the pawls nested with the center portion 27 of one pawl received in the cut-away portion 28 of the other pawl to reduce the overall thickness of the assembled pawls while allowing relative pivotal movement between the pawls.

The pawls 17 and 18, the pivot pin 19 and the spring 24 are assembled in a recess 29 formed in the side of the handle 11 which communicates with the opening 16 through the handle. A cover plate 30 is secured to the side of the handle by screws 31 and covers the recess 29 to retain the pawls 17 and 18, the pivot pin 19 and the spring 24 within the recess 29.

A shaft 32 is journaled at one end in the cover plate 30, extends between the extensions 22 and 23 of the pawls 17 and 18 and through the bottom wall 33 of the recess 29 into a recess 34 formed in the opposite side of the handle 11. A finger lever or knob 35 is secured to the end of the shaft 32 which extends into the recess 34 by means of a pivot pin 36, whereby the shaft 32 may be rotated by turning of the lever or knob 35.

As best shown in FIGS. 3, 4 and 5, the portion of the shaft 32 which extends between the extensions 22 and 23 of the pawls 17 and 18 is cut away at 37 and 38 leaving an eccentric cam portion 39. In either the down or up position of the shaft 32, the cut-away portions 37 and 38 provide clearance allowing the spring 24 to move either the pawl teeth 21 or 22 out of engagement with the ratchet teeth 15. The cam portion 39 prevents pivotal movement of the pawls 17 and 18 in a neutral position. In this neutral position of the pawls, the handle 11 may be rotated freely of the shaft 12, so that the operator may rotate the handle to a position which is most convenient for operating the hoist.

If it is desired to lower the hook 13, the lever or knob 35 is rotated in the counterclockwise direction, until the pointed end 35a of the lever 35 points to the word "down" embossed on the side of the handle, as shown in FIG. 1. This results in rotation of the eccentric cam portion 39 of the shaft 32 to the position shown in FIG. 4, resulting in the tooth 20 of the pawl 17 being forced away from the ratchet teeth 15 by the cam portion 39 and the extension 23 of the pawl 18 being released whereby the spring 24 forces the pawl tooth 21 of the pawl 18 into engagement with the ratchet teeth 15 as shown in FIG. 4. On downward pumping movement of the handle 11 the operating shaft 12 will be rotated in the counterclockwise direction with a resulting lowering of the hook 13. On the upward return stroke of the handle 11, the pawl 18 will ride over the teeth 15 through a yielding of the C-shaped spring 24.

Similarly, if the lever or knob 35 is turned in the counterclockwise direction until the pointed end 35a thereof points to the word "up" embossed on the side of the handle as shown in FIG. 1, the eccentric cam portion 39 will be rotated to a position forcing the pawl tooth 21 of the pawl 18 away from the ratchet teeth 15, while allowing the spring 24 to force the pawl tooth 20 of the pawl 17 into engagement with the ratchet teeth 15 whereby the handle 11 may be used to rotate the operating shaft 12 in a clockwise direction to raise the hook 13.

From the preceding description, it can be seen that there is provided a novel pawl arrangement which is simpler, less expensive and more efficient than those heretofore used. Because of the arrangement of the simple C-spring extending around the extensions of the pawls, when one of the pawls is moved away from the ratchet teeth by the cam, the spring is actually tensioned, thereby increasing the force with which the spring urges the other pawl into engagement with the ratchet teeth. The efficiency of the spring for the purpose of engaging the pawl is therefore increased.

While one form of the invention has been shown and described, it will be understood that this is for the purpose of explanation and that changes and modifications may be made therein without departing from the spirit and scope of the invention.

I now claim:

1. In a hoist having an operating shaft and a handle mounted for rotation on said shaft, ratchet teeth on said shaft, a pair of separate pawls, each pawl having a pawl tooth at one end and an extension at the other end, means mounting said pawls in scissors fashion on a common pivot of said handle with the pawl tooth of each pawl extending from one side of said pivot toward said ratchet teeth on said operating shaft and the extension of each pawl extending from the other side of said pivot, C-shaped spring means extending around said extensions and urging said extensions toward each other whereby to urge said pawl teeth toward each other and toward said ratchet teeth, rotatable cam means extending between said spring and said extensions of said pawls, said cam means in one rotated position preventing pivotal movement of either of said pawl teeth into engagement with said ratchet teeth, said cam means in second and third rotated positions pivoting one of said pawls in a direction to move the pawl tooth thereof further away from said ratchet teeth while releasing the other pawl for rotation by said C-shaped spring means in a direction to engage the pawl tooth thereof with the ratchet teeth of said operating shaft whereby said operating shaft can be rotated in one direction by said handle.

2. In a hoist having an operating shaft and a handle mounted for rotation on said shaft, ratchet teeth on said shaft, a pair of separate pawls, each pawl having a pawl tooth at one end and an extension at the other end, means mounting said pawls in scissors fashion on a common pivot of said handle with the pawl tooth of each pawl extending from one side of said pivot toward said ratchet teeth on said operating shaft and the extension of each pawl extending from the other side of said pivot, spring means extending around said extensions and urging said extensions toward each other whereby to urge said pawl teeth toward each other and toward said ratchet teeth, movable cam means extending between said spring and said extensions of said pawls, said cam means in one position preventing pivotal movement of either of said pawl teeth into engagement with said ratchet teeth, said cam means in second and third positions pivoting one of said pawls in a direction to move the pawl tooth thereof further away from said ratchet teeth while releasing the other pawl for rotation by said spring means in a direction to engage the pawl tooth thereof with the ratchet teeth of said operating shaft whereby said operating shaft can be rotated in one direction by said handle.

3. In a hoist having an operating shaft and a handle mounted for rotation on said shaft, ratchet teeth on said shaft, a pair of pawls, each pawl having a pawl tooth at one end and an extension at the other end, means mounting said pawls in scissors fashion on a common pivot in a recess formed in the side of said handle with the pawl tooth of each pawl extending from one side of said pivot toward said ratchet teeth on said operating shaft and the extension of each pawl extending from the other side of said pivot, C-shaped spring means extending around said extensions and urging said extensions toward each other whereby to urge said pawl teeth toward each other and toward said ratchet teeth, a cover for said recess enclosing said pawls, spring, and pivot in said recess, rotatable cam means extending between said spring and said extensions of said pawls, shaft means connected with said cam means and extending from one side of said handle, lever means secured to said shaft means on the outside of said handle for rotating said shaft to rotate said cam means, said cam means in one rotated position preventing pivotal movement of either of said pawl teeth into engagement with said ratchet teeth, said cam means in second and third rotated positions pivoting one of said pawls in a direction to move the pawl tooth thereof further away from said ratchet teeth while releasing the other pawl for rotation by said spring means in a direction to engage the pawl tooth thereof with the ratchet teeth of said

operating shaft whereby said operating shaft can be rotated in one direction by said handle.
